(57) **CLAIM**

The ornamental design for a lacing portion of a shoe upper, as shown and described.

DESCRIPTION

FIG. 1 is a perspective view of the lacing portion of a shoe upper;

FIG. 2 is a front elevational view of the lacing portion of a shoe upper;

FIG. 3 is a left (medial) side elevational view of the lacing portion of a shoe upper;

FIG. 4 is a right (lateral) side elevational view of the lacing portion of a shoe upper; and,

FIG. 5 is a top plan view of the lacing portion of a shoe upper.

Broken lines in the figures, which represent the remaining portions of the shoe, are for illustrative purposes only and form no part of the claimed design.
